UNITED STATES PATENT OFFICE.

PETER RUNDQUIST, OF NEW YORK, N. Y.

BLIND-SLAT ADJUSTER.

SPECIFICATION forming part of Letters Patent No. 335,093, dated January 26, 1886.

Application filed October 20, 1885. Serial No. 180,424. (No model.)

To all whom it may concern:

Be it known that I, PETER RUNDQUIST, of the city, county, and State of New York, have invented a new and useful Improvement in 5 Blind-Slat Adjusters, of which the following is a full, clear, and exact description.

Reference is to be had to the accompanying drawings, forming a part of this specification, in which similar letters of reference indicate 10 corresponding parts in all the figures.

Figure 1 is a front elevation of a part of a blind to which my improvement has been applied, parts being broken away. Fig. 2 is a 15 sectional plan view of the same, taken through the line $\alpha\alpha$, Fig. 1. Fig. 3 is a front elevation of a part of the same, the cup-cap and the thumb-piece being removed. Fig. 4 is an elevation of the inner side of the cap-plate and the eccentric.

20 The object of this invention is to provide blind slat adjusters constructed in such a manner that the blind-slats can be readily adjusted at any desired angle.

The invention consists in the construction 25 and combination of various parts of the blind-slat adjuster, as will be hereinafter fully described, and then pointed out in the claims.

A represents the frame of a blind, and B the blind-slats, which are pivoted to side strips, 30 C, attached to the inner edges of the blind-frame A. The side strips, C, are each made in two longitudinal parts, the plane of division running through the pivot-bearings for the slats B, as shown in Fig. 2, so that any 35 desired slat can be readily removed and replaced by detaching parts of the said side strips.

To one end of each slat B is attached a headed pivot-pin, D, which passes through the side 40 strips, C, and is made of such a length that the head of the said pin will rest against the inner edge of the frame A, and will be held against the said edge by the side strip, C, which is slightly countersunk to receive the 45 said head, so that the said side strip will fit snugly against the said edge of the frame A. By this construction the slats B will be held from longitudinal movement, and will be held out of contact with the outer sides of the side 50 strips, C, and will thus be prevented from marring the paint upon the said side strips as the said slats are turned. To the other ends of the slats B are attached small cranks E, which rock in bearings in the adjacent edges

of the parts of the side strip, C. The stems 55 of the cranks E are made with lugs F upon their opposite sides, which fit into recesses in the ends of the slats B, so that the said slats will be turned by and with the said cranks. The cranks E project into a longitudinal groove, G, 60 in the inner edge of the side bar of the frame A, and are pivoted to a bar, H, also placed within the said groove, the said groove being made wide enough to allow the cranks E and bar H to have the necessary movement. 65

To the bar H is rigidly attached a pin, I, which projects through a slot in the inner end of a plate, J, placed in a recess in the side bar of the frame A, and pivoted at its outer end to the said side bar. The side edges of the 70 plate J are bent outward to form flanges K, between which is fitted a disk, L, which is secured eccentrically to the stem of the thumb-piece M. The stem of the thumb-piece M passes through a hole in the center of the bottom of the cup cap-plate N, which is secured in a recess in the side bar of the frame A, and which is made of such a depth that the said thumb-piece will not project above the surface of the side bar of the frame, and of such 75 size that the said thumb-piece can be readily grasped and operated to adjust the slats B at any desired inclination.

Having thus fully described my invention, I claim as new and desire to secure by Letters 80 Patent—

1. In a blind-slat adjuster, the combination, with the frame A, the slats B, and the side strips, C, of the cranks E, attached to the blind-slats, the bar H, connecting the said cranks, 90 and provided with a pin, I, the slotted and flanged pivoted plate J, the eccentric L, and the thumb-piece M, substantially as herein shown and described, whereby the blind slats can be readily adjusted to any desired angle, 95 as set forth.

2. In a blind-slat adjuster, the combination, with the blind-slats B, having end recesses, of the cranks E, having side lugs, F, on their stems to engage with the said recessed ends 100 of the slats, substantially as herein shown and described, whereby the said cranks are made to turn the said slats, as set forth.

PETER RUNDQUIST.
